ELEVATOR CONTROL AND SIGNAL SYSTEM

Harold W. Williams, Englewood, and Danilo Santini, Tenafly, N. J., assignors to Westinghouse Electric Elevator Company, Jersey City, N. J., a corporation of Illinois

Application January 12, 1938, Serial No. 184,694

28 Claims. (Cl. 187—29)

Our invention relates to systems of control for electric elevators and more particularly to such systems in which a number of elevator cars operating together as a bank are controlled by passenger-operated push buttons located at the various floor landings. Although not limited thereto, our invention is particularly applicable to such elevator systems in which the elevator cars are driven at relatively high speeds by variable-voltage or other high-speed motive equipment and are automatically stopped at the floors by automatic landing equipment or equivalent apparatus. Such elevator systems provide the most efficient passenger service available and find their principal application in office buildings and other tall structures having a large number of floors and a relatively large volume of passenger traffic.

In such systems, in the absence of special control provisions which will be described, there is a tendency for the various elevator cars to distribute the building traffic unevenly, and, in the taller buildings, for the cars to become "bunched" and thus prevent reasonable uniformity of spacing between the cars.

These systems also tend to provide better service at certain floors than at others, particularly during the noon and evening rush periods, at which times a relatively large number of calls are registered at practically all floors of the building within a relatively short period of time. At such rush periods, each elevator car is filled to capacity by a relatively few stops, perhaps three or four. Considering a car leaving the upper terminal, such a car is usually required to make these few stops at the upper floors and so passes the lower floors without stopping. Because of the frequency with which calls are registered, the next car of the series is also filled to capacity by three or four stops at upper floors and so passes the lower floors without stopping. In the operation of these systems, therefore, the response to calls registered from lower floors of the building is delayed until most of the traffic from the upper floors has received attention.

In order to provide more uniform service throughout the building during heavy traffic peaks, the "quota system," as disclosed in the Richard W. Jones Patent No. 2,104,522, issued January 4, 1938, and the William F. Eames Patent No. 2,104,478, issued January 4, 1938, to

Westinghouse Electric Elevator Company, has been devised. In accordance with the quota principle, each car is normally assigned a zone of floors extending in advance of itself up to some point of reference such as the next car travelling in the same direction, or, if no car is in advance of it travelling in the same direction, up to the last car travelling in the opposite direction. All corridor calls for service in the corresponding direction of travel, registered at floors included in a car's zone, are assigned to the car as soon as registered, until a predetermined number, or quota, of calls is received. Upon receipt of its quota of calls, the car loses its zone and cannot accept any further calls until it reaches a terminal. The zone of a car which has accepted its quota of calls is transferred to the next following car, so that the zone of the latter extends from its own position, past the car having its quota, up to the next preceding car travelling in the same direction, or to some other reference point.

It has been found in practice that the quota system distributes the acceptance of calls between upper and lower floors satisfactorily during heavy traffic conditions, and this system provides a more uniform time interval between the operation of a push button and the stopping of a car in response thereto, throughout the entire range of floors served by the system. Because of this more uniform time interval, the percentage of stops which result in the picking up of a single passenger is decreased; the average number of passengers picked up per stop is increased; the average number of stops per trip is decreased; and the average number of trips for the system as a whole per unit times is increased as compared to corresponding values for systems otherwise similar but lacking the quota feature.

We have found, however, that in buildings in which the cars serve a relatively large number of floors, conditions may arise which will cause a particular car to have an unusually long trip time, thereby interfering with the proper dispatching of other cars. Such conditions may arise where the quota is relatively large, for example, seven or eight calls, and the calls are registered at a relatively slow rate.

In one aspect, it is an object of the present invention to shorten the possible trip time by imposing a condition, additional to the quota

limit, which will terminate the ability of a car to accept calls. This condition is the lapse of a predetermined time interval.

Another object of our invention is to provide a novel elevator system in which any down moving car loses its call zone if a car standing at the upper terminal receives a start down signal.

A further object of our invention is to provide a novel elevator system in which an up moving car may receive a start down signal before it reaches the upper terminal, if there are no other cars of the bank at the upper terminal, and a sufficient number of down calls are registered.

Other objects of our invention will become evident from the following detailed description taken in conjunction with the accompanying drawings, in which:

Figure 1 is a diagrammatic view showing the arrangement of two elevator cars A and B in a hatchway, and apparatus associated with the cars.

Figs. 2 to 7, inclusive, are diagrammatic views showing the circuit connections of various electrical elements used in the practice of the invention. These figures may be assembled vertically, in numerical order with Fig. 2 at the top, to illustrate the circuit features of the invention, and

Figs. 2A to 7A are diagrammatic views showing the mechanism relationship of the coils and contacts of various relays shown in Figs. 2 to 7, inclusive. Figs. 2A to 7A may be arranged beside the corresponding Figs. 2 to 7, inclusive, to facilitate location of the various coils and contacts. The coils and contacts of Figs. 2A to 7A are at approximately the same levels, from top to bottom of the figure, as the corresponding elements of Figs. 2 to 7.

In order to reduce circuit complications to a minimum, the control circuits for two cars A and B only, are shown herein. It will be understood, however, that similar circuits would be provided for each car of a bank, which might comprise, for example, six cars. Similarly, the dispatcher has been illustrated as applied to four cars A, B, C and D, it being understood, however, that it may be expanded by a duplication of apparatus for a larger number of cars, as, for example, six cars.

In order to eliminate unnecessary multiplication of parts for the various floors, the invention has been illustrated as applied to a bank of cars operating between first and fifth terminals. It will be obvious, however, that the system may be extended to include as many floors as desired.

Wherever possible, the apparatus which is individual to car B has been given the same reference character as the corresponding element of car A, with the exception that the prefix B is used to indicate that the apparatus is individual to car B. As the operation of car A will be described in detail, the prefix A has been omitted from the reference characters pertinent thereto, in order to reduce the number of characters making up each reference character used in the description.

The control apparatus individual to car A, which is duplicated for the other cars such as car B, is listed below. The control apparatus, except the dispatcher, common to cars A and B is listed in a separate schedule, and the dispatcher apparatus for cars A, B, C and D is listed in a third schedule.

Apparatus shown in Fig. 1 of the drawings

Referring particularly to Figure 1 of the drawings, it will be observed that car A is arranged to be supported in a hatchway by means of a cable 10 which is passed over a sheave 11 and is counterweighted by means of a counterweight 12. The sheave 11 is mounted for rotation with a shaft 13 which is driven by a motor MR. A brake EB of the usual spring operated electromagnetically released type is provided for stopping further rotation of the sheave 11 when the motor MR is deenergized.

A floor selector 15, of any suitable type, is provided for commutating various circuits of the system in accordance with the position of car A. As illustrated, the shaft 13 is extended and is arranged to operate a brush carriage 14 of the floor selector 15 by mechanically rotating a lead screw 16. The brush carriage 14 is provided with a number of moving brushes, each of which successively engages a row of stationary contacts, corresponding to the floors of the building, upon movement of the car. For simplicity, only two moving brushes 50 and 70 and the cooperating two rows of contacts are illustrated, but it will be understood that in practice a much larger number of brushes and rows of contacts are provided. Other forms of selectors may also be used.

In order to effect accurate stopping of car A at floor level, a slow-down inductor relay E and a stopping inductor relay F are mounted upon the car in positions to cooperate with suitable inductor plates UEP, DEP, UFP, DFP of iron or

other magnetic material, mounted in the hatchway. The inductor relays E and F have normally incomplete magnetic circuits which are successively completed by the inductor plates UEP, UFP, or equivalent, as the car approaches floor level. These relays are so designed that energization of their operating coils will not produce contact operation except at such times as the relay is opposite an inductor plate, thereby completing

- 5 the relay magnetic circuit. Upon operation of the relay contacts (such as E1 or E2) the contacts remain in operated condition until the relay operating coil is deenergized, even though the inductor relay moves from a position opposite 10 the inductor plate which completed its magnetic circuit. One pair of up inductor plates, such as UEP and UFP is provided for each floor except the lower terminal, and a pair of down inductor plates, similar to DEP and DFP, is provided for 15 each floor except the upper terminal. Other methods of controlling slow down and stop of the car may be used if so desired.

At each floor, hall lanterns are provided over each hatchway door or at other suitable locations 20 to indicate which car will answer a call. As illustrated in Fig. 1 of the drawings, hall lanterns 2UL and 2DL are illustrated as being individual to car A for the second floor. It will be understood that similar hall lanterns are provided for 25 the other cars and for each floor between the terminals. At the terminal floors, only one lantern is required per car, in accordance with the usual practice.

In order to provide for registering calls at the 30 floors, hall call buttons are provided at each floor intermediate the terminals, one button for each direction of travel. As illustrated, the second floor is provided with an up hall call button 2U and a down hall call button 2D. The other intermediate floors are similarly provided with hall call buttons, and a single button is provided at the terminal floors.

In order to start car A in either direction, a master switch MS is provided within the car in 35 a position convenient to be controlled by the operator. The master switch MS includes an energizing segment which normally stands in a central position but is operable to either of two starting positions, the first in engagement with up contact member MSU for starting car A in the up direction, and the second in engagement with down contact member MSD for starting car A in the down direction. During ordinary operation, the master switch MS is moved to the proper up or down starting position and held in 45 such position until the operator feels the car decelerating, at which time the switch is centered. If at any time the operator wishes to make an automatic stop at the next floor in advance of the car, he may do so by centering the master switch MS. Stopping from car buttons may be used 50 without departing from the scope of my invention.

If the operator wishes to place car A on maintenance operation, or wishes to by-pass calls, he 55 may operate, respectively, the maintenance switch MTS or the manual by-pass switch MBP, which are also carried by the car.

70 Dispatching lights are also provided in the elevator car which indicate to the operator when his car is next to leave a terminal and when it is to start from a terminal. For this purpose, next up light NUL and start up light SUL are provided for operation away from the bottom terminal, and next down light NDL and start

down light SDL are provided for operation away from the top terminal.

Apparatus shown in Fig. 2 of the drawings

Referring particularly to Fig. 2 of the drawings, it will be observed that on the left-hand side control circuits are shown which are individual to car A. At the right-hand side, the circuits shown are individual to car B. Since the circuits are substantially duplicates, reference only will be made to the circuits individual to car A.

As shown, the motor MR is provided with an armature Ma which is connected to the shaft 13 for driving the sheave 11 . The brake EB is provided with a winding EBw which is energized on energization of the motor MR . The motor MR includes the usual shunt-type main field winding Mf , which is connected for energization between supply conductors $L1$ and $L2$. The armature Ma of motor MR may be energized by means of a generator G which is provided with an armature Ga connected in a loop circuit with the armature Ma . In order to control the direction and value of the voltage generated by the armature Ga , a separately excited main field winding Gf is provided for the generator G . A field resistor $R1$ is included in the circuit of field winding Gf in order to provide speed control for the motor MR . The generator G is provided with suitable apparatus for correcting the speed regulation of motor MR , shown for simplicity as a series field winding Gs .

The master switch MS , previously described as located in car A, is here shown connected to selectively control the energization of the operating windings of an up reversing switch U and a down reversing switch D . The reversing switches U and D are provided with contact members, as illustrated, for reversing the connections of the generator field winding Gf to the conductors $L1$ and $L2$, depending upon the direction in which it is desired to operate the elevator car. When either the up or the down reversing switch U or D is energized, a brake relay M is also energized to perform functions which will be set forth hereinafter. In order to apply the maximum voltage to the main field winding Gf , a speed relay V is provided, which is energized on energization of either the up or the down reversing switch U or D to short-circuit a resistor $R1$, connected in series circuit relation with the generator field winding Gf .

A pair of mechanical limit switches VTU and VTD are provided for interrupting the circuit of the high speed relay V when the car reaches a proper slow down point in advance of the upper and lower terminals, respectively, and a pair of stopping limit switches STU and STD are provided for opening the circuits of the reversing switches U and D at the limits, in accordance with the usual practice.

For the purpose of performing certain functions which depend upon the direction of movement of the elevator car, up and down direction preference relays W and X , respectively, are provided. The operating windings of these relays are controlled, respectively, by a limit switch $30t$, individual to the top terminal, and a limit switch $30b$, individual to the bottom terminal. Each of the limit switches $30t$ and $30b$ is arranged to be opened when car A is at the corresponding terminal, thereby interrupting the circuit of the direction preference relay W or X corresponding to the direction approaching the terminal. The di-

rection preference relays W and X are so interlocked that upon opening of one, the other will close.

As set forth hereinbefore, each car is provided with a slowdown inductor switch E and a stopping inductor switch F , the operating coils of which are arranged to be energized on operation of a stopping relay S (contacts $S1$ of which only are shown in Fig. 2), and an auxiliary relay G . The stopping relay S is arranged to be operated upon approach of the car A to a floor for which a hall call is registered, as will be set forth hereinafter. Since the stopping relay S is operated only momentarily, the auxiliary relay G is provided for maintaining the energizing circuit for the operating windings of the slowdown and stopping inductor switches E and F .

In addition to the apparatus shown for controlling the inductor relays E and F in response to hall calls, suitable apparatus is provided for controlling these relays in response to car calls registered from within the car A. However, in order to simplify the description and drawings, the apparatus for registering car calls has been omitted. This apparatus may be of any suitable type, known in the art, effective to permit the registration within the car of stop calls for all floors served by the car for both directions of car travel, and to initiate an automatic stopping operation of the car upon approach of the latter to a floor for which a car stop call is registered.

The floor lanterns and energizing circuits therefor are shown in the lower part of Fig. 2. As indicated above, an up floor lantern, such as lantern $4UL$, and a down floor lantern, such as lantern $4DL$, are provided for each car at each intermediate floor, and are preferably located above the hatchway door for the corresponding car. At the terminal floors, a single floor lantern, such as lantern $5DL$ is provided for each car, in accordance with the usual practice.

Each floor lantern is a means functionally related to the stopping of a car and is connected to be energized by contact members such as $4UY1$ of a zoning relay such as $4UY$ (to be hereafter described) and contacts such as $4UR1$ of a call relay $4UR$ (which will be hereafter described) in series. The lanterns may also be independently energized through segments of the floor selector by means of moving brushes such as 50 , when the direction preference relay, such as W corresponding to the direction of car motion, is closed, and the high speed relay V of the corresponding car is open. The purpose of the latter connections is to maintain the floor lantern energized when the car is standing at a floor, or, during the period that the car is slowing down in approaching the floor.

Apparatus shown in Fig. 3

Each intermediate floor is provided with an up hall button such as $4U$ and a down hall button such as $4D$, which serve to signal a car, in condition to stop at the corresponding floor, travelling in the up or down direction, respectively, in order to prepare the car for an automatic stopping operation at the corresponding floor. Similarly, the terminal floors are provided with a single hall button $1U$ and $5D$, respectively, for registering calls in the direction away from the terminal.

The up hall buttons $1U$, $2U$, $3U$ and $4U$ are connected in energizing circuits for a plurality of up call relays $1UR$, $2UR$, $3UR$ and $4UR$, which serve to store calls for service registered from

the corridors, to be answered by the first approaching car, in condition to stop, travelling in the proper direction. A similar call relay 5DR is provided to store the calls registered by the upper terminal hall button 5D.

Each of the call relays 1UR, 2UR, etc., comprises an energizing coil, which bears the same designation as the relay as a whole, and a demagnetizing winding, such as 5DRN, which when energized counteracts the tractive effort of the energizing coil, thereby causing the relay armature to drop out. The demagnetizing coils 5DRN, 4URN, etc., are connected to stationary segments 65, 64, etc., to be energized when the corresponding car approaches the floor individual to the relay, in condition to make an automatic landing. It will be noted that each of the demagnetizing coils 5DRN, etc., is connected to stationary segments of the floor selectors of both cars A and B, so that the approach of either car to the corresponding floor, in condition to make an automatic landing, will cause the demagnetizing winding of the relay to be energized.

In place of the common call relays for each floor as described for the up direction of car travel, an individual down call relay 4DR, 3DR, etc., is provided for each car for each intermediate floor, for the down direction. The down call relays 4DR, 3DR, etc., are similar structurally to the up call relays 4UR, etc. However, the energizing coils of the down call relays 4DR, B4DR, etc., for each floor are connected in parallel groups to be energized by a common down hall button 4D, etc., and are provided with interlocking contacts such as 4DR2, B4DR2, etc., so connected as to prevent more than one down call relay of the group being closed at the same time. The particular down call relay 4DR, B4DR of our floor group which will respond to operation of the corresponding hall button 4D, is determined by the car having the "down zone" which includes the particular floor, as will be hereinafter more fully explained.

A stopping relay S is provided for initiating an automatic stopping operation of the car A at any floor at which the latter car is selected for a stop in response to operation of one of the call relays 5DR, etc. The stopping relay S is controlled by means of two separate stopping circuits for the up direction of car travel and for the down direction, respectively, each stopping circuit including a separate brush and row of segments of the floor selector 15.

Apparatus shown in Fig. 4

An individual set of down zoning relays 5DY, 4DY, 3DY, etc., which serve to determine the "down zone" and thereby to select the floors at which an automatic stopping operation is to be made, is provided for each car. As in the case of the call relays 5DR, 4DR, 3DR, etc., a single zoning relay 5DY, 1UY, is provided for the terminal floors, and individual up and down zoning relays such as 4UY and 4DY, are provided for each intermediate floor. The zoning relays 4DY, 4UY, etc., for the intermediate floors are provided with demagnetizing windings 4DYN, 4UYN, etc., which serve a similar function to the demagnetizing windings of the call relays 5DR, etc., described above.

The zoning relay 5DY for the upper terminal floor is connected to be closed whenever the down dispatch acceptance relay DE for the corresponding car and the next down relay AND, both of which latter relays will be hereinafter described,

are closed, and the auxiliary pass relay PX and down pass relay PD of the corresponding car are open. The remaining down zoning relays 4DY, 3DY, etc., for the corresponding car, are automatically closed in sequence in response to closure of the terminal zoning relay 5DY, down to a floor at which a zoning relay for some other car is closed. For example, if the zoning relay B2DY for car B is closed, and no zoning relays for the third or fourth floors are closed, upon closure of the terminal zoning relay 5DY for car A, the down zoning relays 4DY and 3DY will automatically close in sequence, but the down zoning relay 2DY will remain open. It will be seen that with this arrangement when any terminal zoning relay closes, the corresponding car takes control of the zone consisting of all of the floors extending away from the terminal up to the floor at which the next car travelling in the same direction is located.

Each car is provided with an up pass relay PU or BPU, which serves, when operated, to permit the corresponding car to pass to the upper terminal without making any automatic stops. A down pass relay PD or BPD is provided for performing a similar function in the down direction of car travel. A pass relay P or BP is provided for each car for initiating operation of the corresponding down pass relay PD or BPD. An auxiliary pass relay PX or BPX is provided for causing the car to pass floors without stopping, under conditions which will be hereinafter more fully described. A manual by-pass switch MBP, BMBP is provided in each car A or B respectively, to effect operation of the corresponding pass relay P or up pass relay PU, depending upon the direction of car travel, at any time that the operator may find it expedient to pass floors at which calls may be registered.

40 A quota relay Q or BQ, is provided for each car for indicating the condition that the total number of calls assigned to the particular car corresponds to the quota of the car, and for setting up control circuits corresponding to the indication. 45 Each quota relay Q or BQ is connected to a plurality of parallel energizing circuits each assigned to supply a definite value of current for the down calls of the corresponding car registered on a corresponding call relay 4DR, 3DR or 2DR. As the cars necessarily must stop at the terminals, it is unnecessary to include the terminal floors in the quota, and call relay contacts for the intermediate floors only are included in the energizing circuit of the quota relay Q.

55 A number of resistors R4DR, R3DR, etc., are included in the parallel branches of the energizing circuit of the quota relays Q and BQ, to provide the definite increments of current corresponding to registered calls. The resistors R4DR, etc., may be all of equal resistance value, or may be weighted to give preference to the calls from some particular floor at which experience shows that a larger number of passengers customarily enter the car. In either event, however, these resistors are designed to have much larger resistance than the coils of the relays Q and BQ, in order to provide approximately the same current increase for each resistor in circuit. For purposes of illustration, it may be assumed that the resistors R4DR, etc., are all of equal resistance value, and that the quota relays Q and BQ each close at a current value corresponding to that provided by two parallel branch circuits. With the quota circuits so designed, the quota of each car is two calls.

Apparatus shown in Figure 5

In addition to the individual zoning relays 5DY, etc., shown in Fig. 4, a set of common zoning relays 1UZ, 2UZ, 2DZ and 1DZ is provided for all of the cars of the bank. In accordance with the principle of our invention, it is unnecessary that an individual common zoning relay be provided for each floor, and the relays may be assigned to zones of several floors, the number of floors per zone preferably decreasing as the terminal is approached. For example, in the up direction of car travel, the common zoning relay 2UZ may be assigned to floors 3 and 4, and the zoning relay 1UZ may be assigned to the upper terminal floor.

Each common zoning relay, such as 2UZ, is connected to the floor selectors of cars A and B, and to contacts of the up direction preference relays W and BW of both cars, in such manner as to be energized when either car is at any place in the common zone, which in this case consists of the third and fourth floors. For this purpose, the moving brushes 90 and B90 of the two floor selectors are made of sufficient length to overlap the adjacent segments such as 95 and 94, to thereby provide continuous energization of the zoning relay 2UZ so long as either car is within the corresponding zone and connected for upward movement.

In addition to the circuits last described, the common zoning relays 1UZ and 1DZ are connected to a group of additional energizing circuits. The latter circuits for zoning relay 1UZ, for example, are effective to produce energization of the latter whenever the down dispatch acceptance relay DE or EDE of either car is closed and the start down relay ASD or BSD of the corresponding car is open.

It will be understood that the common zoning relays 1UZ, 2UZ, 2DZ and 1DZ are provided for dividing the hatchway into zones for all of the cars as a group, and that although the control circuits for only two cars A and B are shown in their entirety, in practice, the common zoning relay for each floor and each direction of car travel would be connected to floor selector segments of all of the cars of the bank for the corresponding floor and direction of car travel, and that one common zoning relay for each direction of car travel would be additionally connected to energizing circuits controlled by the down dispatch acceptance relays and start down relays, etc., of all of the cars.

The manual maintenance switch MTS or BMTS for each car is connected to control the connections of the down dispatch acceptance relay DE and up dispatch acceptance relay UE of the corresponding car. The manual maintenance switch MTS may be opened to remove the corresponding car from control of the dispatcher, and, with the switch MTS in open condition, the corresponding car will operate on maintenance. By maintenance operation is meant the operation of any car as a unit, separated from control of the dispatcher, usually for purposes of adjustment or repair. With both maintenance switches MTS and BMTS closed, as shown in the drawings, both cars A and B are under control of the dispatcher. With the maintenance switches MTS and BMTS closed, the operation of the acceptance relays DE, UE, etc., depends upon the open or closed condition of the various common zoning relays 1UZ, 2UZ, etc., and of the position and direction of travel of the corresponding car, as indicated by the position of its floor se-

lector and the open or closed condition of its direction preference relays W and X and terminal relays TT and LT.

Each car is provided with a next down lamp, such as ANDL, and a start down light such as ASDL, the purpose of which is to notify the operator to prepare his car for starting in the down direction, and to start it in the down direction, respectively, at times determined by the dispatcher. Similar dispatch lamps ANUL and ASUL are provided for the upward direction of car travel.

Each car is provided with a lower terminal relay LT or BLT, which is energized from the corresponding floor selector when the car is at the lower terminal or first floor. Similarly, an upper terminal relay TT or BTT is provided to be energized when the car is adjacent the upper terminal or fifth floor.

Apparatus shown in Figure 6

A relay chain comprising next down relays AND, BND, CND, etc., for each car, together with suitable down chain driving relays DK and DJ, is provided for sequentially energizing the next down lamps ANDL, etc., of the various cars at the intervals suitable for the ordinary operation of the bank. The open or closed condition of the down chain driving relays DJ and DK is determined by the open or closed condition of a down chain timing relay DF, which latter is designed to close substantially instantaneously upon energization of its operating coil but to remain in operated condition, after deenergization of its operating coil for a short time interval, which may be assumed for purpose of illustration as one quarter second. The desired time interval may be secured by any suitable means such as a resistor DFR connected in parallel to the operating coil to provide an inductive discharge circuit for the coil of the relay DF upon disconnection of the latter from the supply conductors L1 and L2.

The down chain timing relay DF is controlled by contacts of the down chain driving relays DJ and DK, and also by a number of parallel circuits, each of which includes back contact members such as ASD3 of the start down relays, front contact members such as AND5 of the corresponding next down relay, and front contact members such as DE5 of the down dispatch acceptance relay DE for the corresponding car.

The relay chain consisting of the next down relays AND, BND, etc., driving relays DK, DJ, and timing relay DF, operates generally as follows: The driving relays DJ and DK open sequentially or close sequentially under control of the timing relay DF, until a condition is reached in which the timing relay DF is closed, and both chain driving relays DJ and DK are either both open or both closed. Until such a condition is reached, the relays DF, DJ and DK operate sequentially and at intervals cause the energization of the next down relays AND, BND, CND, etc., in a repeating sequence until one or the other of the above described conditions of the relays DF, DJ and DK exists.

In order to prevent short circuits between the supply conductors L1 and L2 under certain conditions of operation of the chain driving relays DJ and DK, a resistor R2 is provided in series with the operating coils of the latter relays.

The chain relays AND, BND, etc., pick up and drop out in response to operations of timing the relay DF and the driving relays DK and DJ. The operation of these latter relays goes through a

cycle for each operation of the relay DF. This cycle can best be understood by considering these relays apart from the other circuits. When the control switch supplying voltage to these relays is closed, DJ, DF and DK are energized in the sequence given:

L1; DK3; DF1; DK2; coil DJ; R2; L2.
L1; coil DF; DJ1; DK8; L2.
L1; coil DK; DJ1; coil DJ; R2; L2.

Contact DK8 opens the circuit to coil DF which drops to the deenergized position, after a time delay of, we will assume in this example, $\frac{1}{4}$ second. A short is placed on coil DJ through the circuit:

Coil DJ—DJ1—DK1—DF1—DK4—coil DJ

which thereupon drops out, reenergizing coil DF:

L1—coil DF—DK7—DJ6—L2

Relay DF, in picking up deenergizes coil DK by opening the following holding circuit:

L1 coil DK—DK1—DF1—DK4—R2—L2

Contact DK1 opens and again interrupts the circuit to coil DF which drops to the deenergized position in $\frac{1}{4}$ second and in so doing reestablishes the circuit to energize coil DJ:

L1—DK3—DF1—DK2—coil DJ—R2—L2

The aforementioned sequence will repeat indefinitely.

Relays AND, BND, etc., are now connected to these relays. When the switch was first closed AND became energized:

L1—coil AND—BND3—CND3—DND3—L2 and
L1 coil AND—AND3—DK5—L2 (holding).

Coil BND is then energized:

L1—coil BND—AND4—DJ3—L2

which opens the pick up circuit to coil AND.

Then DK picks up, opening the holding circuit to coil AND, which drops out.

Relay BND remains up as long as both DK and DJ are energized. When DF times out and DJ drops, CND becomes energized:

L—coil CND—BND5—DJ2—L2

Coil BND is held energized through its holding circuit:

L1—coil BND—BND4—DK6—L2

and when DK drops, BND drops out because DK6 opens. Coil CND is held in through its holding circuit:

1L—coil CND—CND4—DK5—L2

Coil CND then remains energized as long as both relays DJ and DK are energized.

However, when DJ picks up a second time relay DND picks up also through:

L1—coil DND—CND5—DJ3—L2

Relay CND will then drop out and DND will remain energized while relays DJ and DK are energized.

When relay DJ drops for the second time, relay AND is again energized, and will remain energized until DJ and DK pick up for the third time.

Thus relays AND, BND, CND and DND pick up, one after another at intervals of $\frac{1}{4}$ second under the influence of relays DJ, DF and DK, and will continue to do so indefinitely until something stops the motion such as one of the three lower circuits to coil DF becoming closed to pre-

vent the deenergization of coil DF by the upper two circuits as previously described. It is to be understood that the $\frac{1}{4}$ second delay may be changed to any other desired interval. For instance, in some cases it may be desirable to use a delay of $\frac{1}{2}$ second.

In addition to the down dispatching relay chain described above, an up dispatching relay chain, comprising up driving relays UJ and UK, next up relays ANU, BNU, CNU, etc., and an up chain timing relay UF, is provided for energizing the next up signal lamps in the same manner as the down relay chain described above.

A down restarting relay TDM, which serves to energize the start down relays of the various cars at time intervals determined by timing elements to be described, is connected in series with a resistor TDMR to the supply conductors L1 and L2, so as to be energized at all times when its operating coil is free from short circuits. The operating coil of the down restarting relay TDM is normally short circuited through a circuit which includes contacts of a quota dispatch relay QN, an instant dispatch button IDB, back contacts of the down restarting relay TDM in series, and back contacts of a group of down timing relays 1TD, 2TD, 3TD, etc., the latter back contacts being connected in parallel.

The operating coil of relay TDM may also be short circuited whenever the quota dispatch relay QN is open and any one of the start down relays ASD, BSD, etc., for the various cars, is closed. With this circuit arrangement the relay TDM is normally short circuited but may be energized when either the quota dispatch relay QN or the instant dispatch button IDB is operated, or when all of the down timing relays 1TD, 2TD, etc., are closed. When the down restarting relay TDM is energized, it may be dropped out in response to closure of any start down relay ASD, etc. or upon opening of all of the down timing relays 1TD, 2TD, etc., assuming in either case that the quota dispatch relay QN is open.

The down timing relays 1TD, 2TD, 3TD, etc., are connected to be closed in sequence by means of contacts T3, T4, T5, etc., of a motor driven timer TMR, to be hereinafter described in connection with Fig. 7, and each timing relay is connected to establish a holding circuit for itself upon its closure. The down timing relays 1TD, 2TD, etc., are connected to be dropped out as a group upon closure of the down restarting relay TDM.

An up restarting relay TUM, similar to the down restarting relay TDM, is connected in a similar circuit with a resistor TUMR. The up restarting relay TUM is controlled by contacts of the quota dispatch relay QN, and by contacts of the start up relays ASU, BSU, etc., and of a group of up timing relays 1TU, 2TU, 3TU, etc., in a manner which will be readily understood from the above description of the down restarting relay TDM.

Apparatus shown in Figure 7

The circuits for the start down relays ASD, BSD, CSD and DSD are shown at the top of Fig. 7. It should be noted that each of these relays can be closed only when the next down relay for the corresponding car, such as relay AND, is closed, the down restarting relay TDM is closed, and either the corresponding quota relay Q or the corresponding upper terminal relay TT is closed. Each of the start down relays ASD, BSD, etc., is connected to establish a holding circuit for itself independent of the contacts of the down restart-

ing relay TDM and of the next down relays AND, etc., upon its closure.

The motor-driven timer referred to above is shown diagrammatically at TMR. The timer TMR consists of a shunt type motor having its armature connected in series with a resistor RTM and in adjustable potentiometer relationship to a speed controlling resistor SMR, energized from the supply conductors L1 and L2. The shunt field TMRS of the timer motor is preferably connected directly to the supply conductors L1 and L2. The timer motor TMR is provided with any suitable mechanical arrangement, shown for simplicity as a shaft and a number of cams, for causing certain contacts to open and others to close in a timed sequence. In order to avoid unnecessary duplication, only contacts T1 to T7 are shown in connection with the motor TMR, but it will be understood that other contacts having the prefix T are similarly controlled. In the arrangement shown, the back contacts T1 and T2 open at the same instant that front contacts T3 close, and front contacts T4, T5, T6 and T7 close sequentially thereafter. The time interval elapsing during a closing cycle of the contacts T1 to T7 is that which determines the interval between dispatcher starting signals, and this time interval is adjusted by varying the speed of motor TMR to suit the condition of the system.

The energizing circuit for the quota dispatch relay QN is shown in the lower right part of Fig. 7. The latter relay is connected to close when the quota relay Q, etc., of any car is closed, and the corresponding up direction preference relay W or the corresponding upper terminal relay TT is closed. No holding circuit is provided for the quota dispatch relay QN.

In the following description of operation, circuits will be indicated wherever possible in a single line by the symbols for the elements included in the circuit, reading from left to right, no verbal designation of the elements being included.

Operation of the system

The operation of the above-described apparatus may be set forth as follows: It will be assumed, initially, that all four cars A, B, C, and D controlled by the dispatcher are standing at the upper terminal and that car A has the next down signal. It will also be assumed that the manual maintenance switches MTS of car A and BMTS of car B, as well as the corresponding switches for cars C and D (not shown) are closed.

Referring to the central part of Fig. 2, as car A is standing at the upper terminal, its upper terminal floor switch 30t is open, and the up direction preference relay W for car A is, accordingly, deenergized. As the back contacts W1 of up direction preference relay W are closed, a circuit is completed for the down direction preference relay X, which circuit will be obvious from the figure. The down direction preference relay X is, accordingly, closed.

As car B is also standing at the upper terminal, a corresponding circuit for its down direction preference relay BX is complete, and the latter relay is also closed.

As car A has the next down signal, the corresponding next down relay AND is closed (top of Fig. 6), and the down chain driving relays DJ and DK are both open. The sequence of operations of the relay chain by which this condition is brought about is not here described, as a sim-

ilar sequence of operations is described below under the heading Down moving car takes up zone from lower terminal. However, it may be mentioned that both relays DJ and DK are open when either car A or car C has the next down signal, and both relays DJ and DK are closed when either car B or car D has the next down signal. The down chain timing relay DF is, under the condition that car A has the next signal, energized through a holding circuit which may be traced as follows:

L1; DF; ASD3; AND5; DE5; L2

Referring to the central part of Fig. 5, a circuit is also complete for the down dispatch acceptance relay DE, which circuit may be traced as follows:

L1; MTS; DE; 115, 110; TT3; L2

Similarly, the down dispatch acceptance relay BDE of car B is energized by means of a circuit which will be obvious from that traced above in connection with relay DE.

The upper terminal relays TT of car A and BTT of car B (bottom of Fig. 5) are energized through segments controlled by the floor selectors of the respective cars as will be obvious from the figure.

With the cars A, B, C and D all standing at the upper terminal, car A having the next down signal, the dispatch acceptance relays DE and BDE; the down direction preference relays X and BX; the upper terminal relays TT and BTT; the next down relay AND, and the down chain timing relay DF are all energized as indicated above. As no cars are standing at or approaching the lower terminal, the up dispatching relay chain relay (upper right part of Fig. 6) is continuously "notching around" in a manner to be described below under the heading Down moving car takes up zone from lower terminal.

In response to closure of the down direction preference relay X, the down floor lantern 5DL for the fifth floor (lower part of Fig. 2) is energized through a circuit which may be traced as follows:

L1; 5DL; 58; 59; X2; V4; L2

Similar energizing circuits for the fifth floor lantern B5DL for car B, and for corresponding lanterns (not shown) for the cars C and D, are also energized.

In response to the closure of the down dispatch acceptance relay DE, a circuit is completed for the up common zoning relay 1UZ (upper part of Fig. 5), which circuit may be traced as follows:

L1; 1UZ; DE2; ASD1; L2

Establishment of down zone from upper terminal

As the next down relay AND and the upper terminal relay TT of car A are both closed, a circuit is completed for the down zoning relay 5DY (top of Fig. 4) which will be obvious from the figure, and, in response to completion of the circuit, the down zoning relay 5DY for car A closes. The down zoning relay 5DY in closing completes a circuit for the down zoning relay 4DY for the fourth floor, for car A, which may be traced as follows:

L1; 4DY2; B4DY2; 5DY2; 4DY; PX1; PD3; L2

As the down zoning relay 4DY is energized through the circuit just traced, it closes and establishes a holding circuit for itself through its front contacts 4DY3 and also establishes an

energizing circuit for the down zoning relay **3DY** for the same car and the next lower floor. Similarly, the down zoning relay **3DY** closes, completing a holding circuit for itself, and also completing an energizing circuit for the down zoning relay **2DY** for the same car and the next lower floor. It will be seen, therefore, that in response to energization of the down zoning relay **5DY** for the fifth floor, the down zoning relays **4DY**, **3DY** and **2DY**, for car A close in sequence. It will be noted, however, that the corresponding energizing circuits for the series of down zoning relays **B4DY**, **B3DY** and **B2DY** of car B are all opened by contact members **4DY2**, **3DY2**, etc. (left upper part of Fig. 4), of the down zoning relays **4DY**, etc., of car A. The closure of down zoning relays **5DY**, **4DY**, **3DY** and **2DY** give the down zone from the upper terminal to car A. As there are no down traveling cars in the hatchway, the down zone extends the full length of the hatchway to the lowest floor at which a down call can be registered, which, for the system described is the second floor.

Operation of dispatcher to provide start signal

Referring to Figs. 6 and 7, the timer motor TMR (Fig. 7) is in continuous rotation causing closure of the timer contacts **T3** to **T7** in sequence. The timer contacts **T1** and **T2**, as indicated above, open at the same instant that contacts **T3** close. Upon closure of timer contacts **T3**, a circuit is completed for the down timing relay **1TD**, and the latter relay closes to establish a holding circuit for itself through its front contacts **1TD2**, and also to open its back contacts **1TD1** in the circuit of the down restarting relay TDM. Similarly, as the timer motor TMR rotates further, the timer contacts **T4** close to complete a circuit for the down timing relay **2TD**. Upon completion of the latter circuit, the down timing relay **2TD** closes to establish a holding circuit for itself through its front contacts **2TD2**, and to open its back contacts **2TD1** in the circuit of the down restarting relay TDM. The down timing relays **3TD**, **4TD** and **5TD** similarly close under control of the timer motor; each, in closing, establishing a holding circuit for itself and opening back contacts in the circuit of the down restarting relay TDM.

Upon closure of all of the down timing relays **1TD**, etc., the short circuit normally existing around the operating coil of the down restarting relay TDM is interrupted, and the latter relay closes. The down restarting relay TDM in closing completes a circuit for the start down relay ASD of car A (top of Fig. 7), which circuit may be traced as follows:

L1; TDM5; AND6; ASD; TT4; L2

In response to completion of this circuit, the start down relay ASD closes. The start down relay ASD of car A, in closing, establishes a holding circuit for itself through its contacts **ASD5**; opens the circuit of the down timing relay DF (central part of Fig. 6); reestablishes the short circuit around the down restarting relay TDM, to thereby cause the latter relay to drop out; and opens the circuit of relay **1UZ** (Fig. 5), causing the latter relay to drop out. The short circuit established around the down restarting relay TDM includes contacts **QN1** of the quota dispatch relay QN and contacts **ASD4** of the down start relay ASD.

Referring to the lower part of Fig. 5, the clo-

sure of start down relay ASD also completes an energizing circuit for the start down lamp ASDL of car A. Upon illumination of the start down lamp ASDL, the operator of car A closes the hatchway door and car gate and starts car A in the down direction.

Transfer of next down signal to another car upon receipt of start down signal

10 In response to the short circuit around the operating coil of the down restarting relay TDM produced by the start down relay ASD, in closing, the relay TDM drops out. The down restarting relay TDM in dropping out prepares 15 the down timing relays **1TD**, **2TD**, **3TD**, etc. (lower part of Fig. 6), for reenergization under control of the motor driven contacts **T3**, **T4**, **T5**, etc.; establishes an additional short-circuit around its own operating coil through its contacts **TDM3** (central left part of Fig. 6); and opens its contacts **TDM5** in the circuit of start down relay ASD (top of Fig. 7). As the start down relay ASD is energized through its own holding contacts **ASD5**, however, it remains closed notwithstanding the opening of contacts **TDM5**.

As the circuit of down chain timing relay DF was opened in response to closure of the start down relay ASD, the relay DF drops out at the expiration of its time element of one-quarter second. The down chain timing relay DF, in dropping out, completes an energizing circuit for the down chain driving relay DJ (upper part of Fig. 6), which may be traced as follows:

L1; DK3; DF1; DK2; DJ; R2; L2

35 The down chain driving relay DJ accordingly closes, completing an energizing circuit for the down chain driving relay DK (top of Fig. 6) by means of its contacts **DJ1**, which energizing circuit, however, is ineffective as the operating coil of relay DK is short-circuited at this time. The down chain driving relay DJ, in closing, also opens its contacts **DJ2**, **DJ4** and **DJ6** (all on Fig. 6) which are at this time ineffective; completes a circuit for the next down relay BND (Fig. 6) by means of its contacts **DJ3**; and recloses the circuit of down chain timing relay DF at its contacts **DJ1**.

The next down relay BND for car B, and the down chain timing relay DF, accordingly, pick up. The down chain timing relay DF, in picking up, removes the short-circuit existing around the operating coil of down chain driving relay DK, thereby causing the latter relay to close.

55 The next down relay BND, in closing, completes a circuit for the individual zoning relay **B5DY** (upper right part of Fig. 4) of car B for the upper terminal floor; completes an energizing circuit for the next down lamp BNDL of car B (lower right-part of Fig. 5); completes a holding circuit for itself through its contacts **BND4** (upper left part of Fig. 6); prepares a circuit for the subsequent energization of next down relay CND by means of its contacts **BND5** (Fig. 6); completes a holding circuit for the down chain timing relay DF (Fig. 6) by means of its contacts **BND3**; and prepares a circuit for the subsequent energization of start down relay BSD (upper part of Fig. 7) by means of its contacts **BND1**.

70 As the down restarting relay TDM, in dropping out, prepared the down timing relays **1TD**, **2TD**, etc., for reclosure under control of the motor driven contacts **T3**, **T4**, etc., the relay **1TD**, **2TD**, **3TD**, **4TD** and **5TD** are reclosing in the relatively slow timed sequence necessary to provide proper dispatch intervals.

As the picking up of down chain timing relay DF removed the short-circuit existing around the coil of down chain driving relay DK (Fig. 6), the latter relay recloses to prepare a circuit for the subsequent short-circuiting of relay DJ by means of its contacts DK1, DK2, DK3 and DK4 (top of Fig. 6); to open the holding circuit of next down relay AND at contacts DK6, causing relay AND to drop out; and to open the closing circuit of down chain timing relay DF at contacts DK8, thereby preparing relay DF for subsequent opening upon interruption of its holding circuit.

The next down relay AND, in dropping out, opens the circuit of down zoning relay 5DY (Fig. 4) causing the latter relay to drop out; and opens circuit of next down lamp ANDL (bottom of Fig. 5). The relay AND also opens the contacts AND3, AND4, AND5 and AND6, without effect at this time.

With the apparatus in the condition so far described, cars B, C and D are standing at the upper terminal; car A is starting down from the upper terminal; the zoning relays 4DY, 3DY and 2DY of car A are closed; the zoning relay 5DY of car B is closed; relays DF, DJ and DK of the down dispatcher are closed; the start down relay ASD of car A is closed, giving the latter car the start signal, and the next down relay BND is closed giving the next down signal to car B.

Starting of car

Referring to Fig. 2, in order to start car A in the down direction, the operator rotates the car master switch MS in the clockwise direction, thereby completing a circuit for the down direction switch D and the brake relay M. This circuit may be traced as follows:

L1; MS; MSD, F2; STD; D; M; SDV; L2

Upon completion of the circuit just traced, the down direction switch D and brake relay M close. The down direction switch D, in closing, connects the main generator field winding Gf to supply conductors L1 and L2 in series with the field resistor R1, by means of its contacts D1 and D3 (Fig. 2); completes an energizing circuit for the release winding EBw of the electromagnetic brake by means of its contacts D2 (Fig. 2); completes a circuit for the high-speed relay V by means of its contacts D4 (Fig. 2) and completes a holding circuit for itself and brake relay M by means of its contacts D5 (Fig. 2). The brake relay M, in closing, prepares a circuit for the subsequent energization of auxiliary relay G and the two inductor relays E and F (Fig. 2), by means of its contacts M1; and opens its contacts M2 (central part of Fig. 3) to prevent the deenergization of any call relays by car A until the latter stops.

In response to energization of its main field winding Gf, the generator G develops a voltage which causes the motor MR to rotate and drive car A in the downward direction. The energization of the high-speed relay V in response to closure of the contacts D4 of down direction switch D, mentioned above, causes the field resistor R1 to be short circuited, thereby increasing the excitation and voltage of the generator G to cause the motor MR to accelerate to maximum speed.

As car A leaves the upper terminal, the brush t1 of the floor selector (lower left part of Fig. 5) leaves the stationary segment t2, causing the upper terminal relay TT to drop out. The upper terminal relay TT, in dropping out, opens the circuit of down dispatch acceptance relay DE (central left part of Fig. 5); and also opens the

circuit of the start down relay ASD for car A (top of Fig. 7) thereby causing both relays DE and ASD to drop out.

The down dispatch acceptance relay DE, in dropping out, opens its contacts DE1, DE2, DE3 and DE5, without effect at this time; and opens the circuit of start down lamp ASDL (lower part of Fig. 5) at contacts DE4. The start down relay ASD, in dropping out, opens its contacts ASD1, ASD2, ASD3, ASD4, and ASD5, without effect, except in the preparation of circuits for further operation.

Registration of hall call for down direction

Assuming that a prospective passenger at the third floor wishes to register a call for a down moving elevator car, he operates the down call button 3D (central part of Fig. 3) thereby completing an energizing circuit for the down call relay 3DR. The latter circuit may be traced as follows:

L1; 3D; 3DR2; B3DR2; C3DR2; 3DY1; 3DR; L2

The down call relay 3DR accordingly closes, completing a holding circuit for itself by means of its contacts 3DR4 (Fig. 3); completing an energizing circuit for the down floor lantern 3DL by means of its contacts 3DR1 (lower part of Fig. 2); opening the energizing circuits of all other down call relays for the third floor by means of its contacts 3DR2 (Fig. 3); preparing a pass circuit for subsequent energization, by means of its contacts 3DR4; (Fig. 3) and partially completing a circuit for the stopping relay S by means of its contacts 3DR6 (lower part of Fig. 3). The down call relay 3DR, in closing, also registers one call upon the quota relay Q (lower part of Fig. 4), by completing a parallel branch circuit through the quota resistor R3DR. As the quota of car A is two calls, the current traversing the resistor R3DR is insufficient to effect energization of the quota relay Q, and the latter relay remains open.

Operation of quota relay

Assuming that a second prospective passenger at the second floor desires to register a call for a down moving car, he operates the hall button 2D, which completes a circuit for the down call relay 2DR, similar to that traced above for the down call relay 3DR. The down call relay 2DR accordingly closes to perform similar operations to those specified above in connection with call relay 3DR, including the completion of a second branch energizing circuit for the quota relay Q. The down call relay 2DR completes its energizing branch circuit for the quota relay Q by means of its contacts 2DR1, as shown in the lower part of Fig. 4. Upon closure of the latter contacts, the current traversing the quota relay Q is approximately doubled, and the latter relay closes.

The quota relay Q, in closing, closes its contacts Q2 in the circuit of start down relay ASD (Fig. 7), and its contacts Q3 in the circuit of quota dispatch relay QN (Fig. 7), both of which operations are ineffective as the circuits commutated are open at other points. However, the quota relay Q also establishes a closing circuit for the auxiliary pass relay PX (lower part of Fig. 4) which may be traced as follows:

L1; LT1; PX; Q1; L2

In response to completion of this circuit, the auxiliary pass relay PX closes to effect opening of the quota relay Q by means of its contacts

PX3 (lower part of Fig. 4); to establish a holding circuit for itself by means of its contacts **PX2** (lower part of Fig. 4) and to effect deenergization of the down zoning relays **4DY**, **3DY**, etc., by means of its contacts **PX1** (upper part of Fig. 4).

In response to the closure of auxiliary pass relay **PX**, the quota relay **Q** and the down zoning relays **4DY**, **3DY** and **2DY** all drop out. The down zoning relays **4DY**, **3DY**, etc., in opening, effect closure of their back contacts **4DY2**, **3DY2**, etc., thereby making it possible to complete the energizing circuits for any other set of down zoning relays, corresponding to a different car, such as car B. As the down zoning relay **B5DY** of car B is closed, the latter car has the down zone immediately above the zone lost by car A. The down zoning relays **B4DY**, **B3DY** and **B2DY** of car B therefore close in sequence to transfer the zone formerly assigned to car A to car B.

Down moving car takes up zone from lower terminal

The dispatcher operation so far described has involved only the down dispatch elements shown in the left part of Fig. 6. The dispatch elements shown in the right part of Fig. 6, corresponding to the up direction, are in continuous operation, assuming that no cars are at the lower terminal, as may be seen from the following: Considering first the operation of relays **UJ**, **UF** and **UK** independently of other elements, a circuit is initially completed for the up chain driving relay **UJ** which may be traced as follows:

L1; **UK4**; **UF1**; **UK2**; **UJ**; **BR2**; **L2**

The up chain driving relay **UJ**, accordingly, closes establishing an energizing circuit for the up chain timing relay **UF** by means of its contacts **UJ1**, and completing a circuit for the up chain driving relay **UK** by means of its contacts **UJ1**. The up chain driving relay **UK**, however, does not close in response to closure of the contacts **UJ1**, as a short circuit is maintained through the contacts **UK4**, **UF1** and **UK2**.

In response to completion of an energizing circuit for the up chain timing relay **UF** by contacts **UJ1**, the former relay **UF** opens contacts **UF1** to interrupt the short circuit around the operating coil of the up chain driving relay **UK**, and the latter relay closes. Relay **UK**, in closing, interrupts the energizing circuit of the up chain timing relay **UF** by opening of its contacts **UK1**.

The up chain timing relay **UF** accordingly becomes deenergized, and, at the expiration of its time element of $\frac{1}{4}$ second, closes its back contacts **UF1** and short circuits the up chain driving relay **UJ**. The up chain driving relay **UJ**, therefore, drops out to again complete a circuit for the up chain timing relay **UF**, by means of its back contact **UJ6**, and the timing relay **UF** again closes, but this time opens the circuit of the up chain driving relay **UK** by means of its contacts **UF1**.

In response to opening of its circuit, the up chain driving relay **UK** drops out thus opening its contacts **UK8** to interrupt the circuit of the up chain timing relay **UF**, thereby restoring the three relays **UJ**, **UK** and **UF** to the condition from which the sequence was initially described. It will be seen that the relays **UJ**, **UF** and **UK** close and open in a continuous sequence.

During the sequential operation of the up chain driving relays **UJ** and **UK** and the up chain timing relay **UF**, the next up relays **ANU**, **BNU**,

CNU, etc., are automatically reclosed in sequence, as will be apparent from the circuits on Fig. 6. This closure of the next up relays **ANU**, **BNU**, etc., however, does not cause any illumination of any of the next up lamps **ANUL**, **BNUL**, etc. (lower part of Fig. 5), as the up dispatch acceptance relays **UE**, **BUE**, etc., are open, and the corresponding lamp circuits are open at contacts **UE4**, **BUE4**, etc.

10 As car A leaves the upper terminal moving downwardly, it approaches the fourth floor, thereby causing contact brush **120** (central left part of Fig. 5) to engage stationary floor selector contact segment **124**. Upon engagement of the brush **120** with the segment **124**, a circuit is completed for the up dispatch acceptance relay **UE** which may be traced as follows:

L1; **MTS**; **UE**; **IDZ1**; **2DZ1**; **124**; **120**; **X10**; **L2**

20 The up dispatch acceptance relay **UE** accordingly closes and thereby appropriates the up zone from the lower terminal to car A, which latter is at this time moving downward, in the vicinity of the fourth floor, but is, nevertheless, the closest car to the lower terminal moving in the downward direction. It should be noted that the fact that car A has lost its down zone does not prevent it from accepting an up zone.

In response to closure of the up dispatch acceptance relay **UE**, a circuit for the up chain timing relay **UF** is partly completed by means of its contacts **UE5** (central right part of Fig. 6). As the next up relays **ANU**, **BNU**, **CNU**, etc., reclose in sequence, a condition is finally reached in

35 which the next up relay **ANU**, by means of its contact **ANU5**, completes the circuit for the up chain timing relay **UF** partially completed by the contacts **UE5** of the up dispatch acceptance relay **UE**. When this condition occurs, the up

40 chain timing relay **UF** can no longer drop out, in its open and closing sequence with the up chain driving relays **UK** and **UJ**, and the continuous reclosing sequence of relays **UF**, **UJ** and **UK** is interrupted. In the circuit condition

45 finally attained, the next up relay **ANU** is closed, and a holding circuit for the latter is complete through its contacts **ANU3** and through the parallel connected back contacts **UJ4** and **UK5** of the driving relays **UJ** and **UK**, which latter relays are open. The relay **UF**, of course, is closed.

Referring to Fig. 4, as the up dispatch acceptance relay **UE** and the next up relay **ANU** are both closed, a circuit is completed for the up zoning relay **1UY**, which circuit may be traced as follows:

L1; **UE1**; **ANU1**; **1UY**; **L2**

The up zoning relay **1UY** for the first floor 60 accordingly closes and causes the successive closure of the up zoning relays **2UY**, **3UY** and **4UY** in the same manner as described above in connection with the down zoning relays **5DY**, **4DY**, etc. The closure of the up zoning relays **1UY**, etc., completes the appropriation of the up zone to the down moving car A, and, if any up calls for the second, third or fourth floors are registered, they will be assigned to car A and will effect instant illumination of the corresponding up floor lanterns for car A.

Automatic landing of car at calling floor

As car A approaches the third floor, the brush 79 (Fig. 3) engages the stationary contact **76**, thereby completing a circuit for the stopping

relay S. The latter circuit may be traced as follows:

L1; 3DR6; 16, 19, X4; PU2; S; PD2, L2

Upon completion of this circuit, the stopping relay S closes and completes an energizing circuit for the auxiliary relay G and the slowdown inductor relay E (central part of Fig. 2), by means of its contacts S1. The stopping inductor relay F is not energized at this time, however, as the back contacts V2 of the high-speed relay V are open. As car A continues to approach the third floor, the slowdown inductor plate (not shown) in the hatchway completes the magnetic circuit of the slowdown inductor relay E, and the contacts E2 of the latter relay open to interrupt the circuit of the high-speed relay V.

Upon interruption of its energizing circuit, the high-speed relay V opens to re-insert the resistor R1 in series with the field winding Gf of generator G and thereby cause the elevator motor MR to decelerate to low speed. The dropping out of the high-speed relay V also causes the establishment of a circuit for the floor lantern 3DL, corresponding to the third floor, which will be effective after the call relay 3DR1 drops out, as long as car A remains in the vicinity of the third floor with its down direction preference relay X closed.

As car A continues to approach the third floor, the stopping inductor relay F arrives at a position opposite the corresponding stopping inductor plate (not shown) for the third floor, and the inductor relay F operates to open its contacts F2 in the circuit of the down direction switch D and the brake relay M. The down direction switch D, accordingly, drops out to disconnect the generator field winding Gf and to deenergize the brake release winding EBw, thereby permitting the brake spring (not shown) to apply the brake and thereby bring car A to rest at the third floor. The brake relay M, in dropping out, interrupts the circuits of the auxiliary relay G and the two inductor relays E and F, thereby preparing these three relays for a further start in either direction. The relay M in dropping out also completes a cancelling or demagnetizing circuit for the down call relay 3DR (left central part of Fig. 3), which may be traced as follows:

L1; PD1; 3DR4; 3DRN; 3DR5; 67, 69, X3; M2; L2

Upon completion of the latter circuit, the call relay 3DR drops out, opening its contacts 3DR1, 3DR3, 3DR4, 3DR5 and 3DR6, and closing its back contacts 3DR2, all of which are ineffective at this time except to prepare circuits for further operation.

Registration of hall call for up direction

Assuming that as car A is standing at the third floor on its down trip, while the remaining three cars B, C and D remain at the upper terminal, a prospective up passenger at the fourth floor operates the up hall button 4U, a circuit is completed for the hall relay 4UR (upper left part of Fig. 3) which will be obvious from the figure. In response to completion of this circuit, the call relay 4UR closes, completing a circuit for the floor lantern 4UL (central part of Fig. 2) by means of its contacts 4UR1; preparing a demagnetizing circuit for its coil 4URN by means of its contacts 4UR2 (upper part of Fig. 3); completing a holding circuit for itself by means of its contacts 4UR3; and preparing a stopping cir-

cuit by means of its contacts 4UR4 (lower central part of Fig. 3).

It will also be assumed that a down passenger at the fourth floor operates the down hall button 4D, thereby completing a circuit for the down call relay B4DR. Upon completion of this circuit, the down call relay B4DR closes, performing operations similar to those described above for the relay 3DR under the heading Registration of hall call for down direction.

It should be noted that the up call relay 4UR is common to all of the cars, whereas the down call relays 4DR, B4DR, etc., are individual to the cars, but are interlocked so that for any calling floor, only the down call relay corresponding to the car having the zone which includes the calling floor can close. The common up call relays 4UR etc., are provided for stopping the first car moving in the up direction which passes a position suitable to stop at a calling floor. However, although any car moving in the up direction may be stopped in response to a registered up call, only the instant signal lamp of the car having the zone is energized in response to the up call, as will be apparent from inspection of the lamp circuits in the lower part of Fig. 2.

Down moving car loses down zone when car at upper terminal receives start down signal

It will be recalled that the next-down relay BND is closed; that the down timing relays 1TD, 2TD, etc., are being sequentially closed under control of the timer motor TMR; that the down chain relays DF, DJ and DK of the dispatcher are closed; and that car B has the down zone extending from the upper terminal, all as described above under the heading Transfer of next down signal to another car upon receipt of start signal. As the quota relay Q has operated, car A has lost its zone. However, in order to illustrate the operation of the subject heading it will be assumed that the down call for the second floor, mentioned above, has not yet been received, and that the quota relay Q accordingly has not operated. Under these conditions, as car A is standing at the third floor, the down zone of car A comprises the second floor only, and that of car B comprises the fifth, fourth and third floors, represented by the closed condition of individual zoning relays B5DY, B4DY and B3DY.

When all of the timing relays 1TD, 2TD, 3TD, 4TD and 5TD have closed, corresponding to the lapse of a complete dispatch interval, the short-circuit normally existing around the down restarting relay TDM (central part of Fig. 6) is interrupted, and the latter relay closes. The down restarting relay TDM, in closing, completes a circuit for the start down relay BSD of car B (top of Fig. 7); interrupts the circuits of all of the timing relays 1TD, 2TD, etc. (lower part of Fig. 6); and completes a circuit for the auxiliary pass relay PX (lower part of Fig. 4) by means of its contacts TDM1. The latter circuit may be traced as follows:

L1; LT1; PX; X8; TT2; TDM1; L2

In response to completion of this circuit, the auxiliary pass relay PX closes to interrupt the circuits of the individual zoning relays 5DY, etc., of car A by means of its contacts PX1 (upper part of Fig. 4); to establish a holding circuit for itself by means of its contacts PX2 (lower part of Fig. 4); and to open the circuit of quota relay

Q by means of its contacts **PX3** (lower part of Fig. 4).

As the individual zoning relay **2DY** is the only down zoning relay of car A closed at the time of operation of auxiliary pass relay **PX**, the zoning relay **2DY** drops out, permitting energization of the down zoning relay **B2DY** of car B, which latter relay immediately closes, as the relay of the same group for the next higher floor (relay **B3DY**) is closed. The opening of relay **2DY** and the closure of relay **B2DY** transfers the down zone previously individual to car A to car B. The latter transfer can also be effected independently of the operation of the dispatcher, by manual operation of the by-pass button **MBP** of car A (lower part of Fig. 4). In order to illustrate the operation of the by-pass, it will be assumed again, that the quota relay **Q** and auxiliary pass relay **PX** have not operated, and it will also be assumed that a single down call for car A exists upon the call relay **2DR**.

Operation of by-pass relay

Assuming that a large number of prospective down passengers are present at the third floor, and that car A takes on a capacity load of passengers, the operator of the latter car operates his by-pass button **MBP** (lower central part of Fig. 4), in order to thereby permit the car to be operated to the lower terminal without further automatic stops in response to hall calls. Upon closure of the by-pass button **MBP**, a circuit for the pass relay **P** is completed through contacts **X1** of the down direction preference relay **X**, and the pass relay **P** closes. The pass relay **P**, in closing, completes pass circuits by means of its contacts **P1**, **P2**, **P3** and **P4** (central left part of Fig. 3) for transferring calls registered on any call relays **4DR**, **3DR** or **2DR**, of car A, to corresponding call relays of any other car having the down zone for corresponding floors. As call relay **2DR** of car A only is energized, and as car B has the down zone for the second floor (relay **B2DY** being closed), a pass circuit is completed for call relay **B2DR** of car B, which circuit may be traced as follows:

L1; P4; 2DR3; P3; B2DY1; B2DR; L2

In addition to completing the pass circuit traced above, the pass relay **P**, in closing, also completes a circuit for the down pass relay **PD** (lower part of Fig. 4) by means of its contacts **P5**, which circuit will be obvious from the figure.

As the closing circuits of down call relay **B2DR** and down pass relay **PD** are complete, the latter relays close. Relay **B2DR** in closing performs similar operations to those described above in connection with relay **3DR**, under the heading Registration of hall call for down direction. The down pass relay **PD**, in closing, opens its back contacts **PD1** (left central part of Fig. 3) in the holding circuit of down call relay **2DR** for car A; opens the circuit of stopping relay **S** (lower left part of Fig. 3); opens its contacts **PD3** (upper left part of Fig. 4) in the circuit of zoning relay **5DY**; and completes a holding circuit for itself by means of its contacts **PD4** (lower left part of Fig. 4).

As the circuit of down pass relay **PD** can be opened only by the lower terminal relay **LT**, and as the down pass relay **PD** prevents energization of stopping relay **S**, car A cannot be stopped in response to down hall calls but will stop at the lower terminal under control of its limit switches.

As soon as the operator of car A releases the

5 by-pass button **MBP**, the pass relay **P** drops out, thereby interrupting the holding circuit of down call relay **2DR** and causing the latter relay to drop out, thereby completing the transfer of the second floor down call to car B.

Car at terminal gets start signal immediately upon filling quota

At the time of closure of down call relay **B2DR**, a previous down call existed for car B at the fourth floor, and the call relay **B4DR** was closed. The closure of relay **B2DR** accordingly completed the quota of car B, causing the quota relay **B** (lower right part of Fig. 4) for car B to close. As car B is standing at the upper terminal, the contacts **BTT5** (lower right part of Fig. 7) are closed, and the closure of quota relay **BQ** completes a circuit for the quota dispatch relay **QN**. The quota relay **BQ**, in closing, also performs various other functions similar to those described for the relay **Q** under the heading Operation of quota relay.

In response to completion of its energizing circuit, the quota dispatch relay **QN** operates to open the short circuits normally existing around the down restarting relay **TDM** and the up restarting relay **TUM** (central part of Fig. 6), thereby causing both of the latter relays to close. The down restarting relay **TDM**, in closing, completes a circuit for the start down relay **BSD** (upper left part of Fig. 7) thereby providing an immediate start signal for car B, without awaiting the lapse of the timing interval ordinarily introduced by the timing motor **TMR** (lower part of Fig. 7). The up restarting relay **TUM** prepares circuits for all of the start up relays **ASU**, **BSU**, **CSU** and **DSU** (upper right part of Fig. 7) but as no cars are standing at the lower terminal, the start up signal is stored until the car having the next up signal arrives at the lower terminal.

It will be recalled that car A is standing at the third floor and cars B, C and D are standing at the upper terminal. Car A has the up zone from the lower terminal but has lost its down zone; and car B has the entire down zone and the start down signal. Down calls at the fourth and second floors are assigned to car B, and the up call at the fourth floor is assigned to car A.

It will be assumed that an additional up call is registered at the third floor by operation of the call button **3U**. This causes closure of the up call relay **3UR**, which performs operations similar to those described under the heading Registration of up hall call. As car A has the up zone from the lower terminal, the closure of up call relay **3UR** effects energization of the floor lantern **3UL**, corresponding to car A.

The operator of car A starts his car downward from the third floor in the manner described, and, upon approach of the car to the lower terminals, the limit switches **UTD** and **STD** (left central part of Fig. 2) bring the car to rest at the lower terminal in a manner which will be understood from the operation described above under the heading Automatic landing of car at calling floor.

In response to the start down signal for car B which remains in effect at this time, the operator of car B starts his car downward in a manner which will be understood from the above-described corresponding operation of car A; answers the down calls existing at the fourth and second floors; and brings car B to rest at the lower terminal.

As car A has the next up signal, the stored start signal, corresponding to the closed condition of up restarting relay TUM, is assigned to car A as soon as the latter arrives at the lower terminal. Referring to Fig. 7, this operation is accomplished by closure of start up relay ASU, the various ancillary operations of which will be understood from the corresponding operations of start down relay ASD, described above under the heading Operation of dispatcher to provide start signal. Upon the assignment of the start up signal to car A, car B receives the next up signal.

Car A having the existing start up signal, its operator starts the car upward, and an automatic landing is effected at the third floor in response to existing third floor up call. Assuming that car A is delayed indefinitely at the third floor, car B receives a start up signal at the expiration of the dispatch interval after the start up signal given to car A.

Lantern transfer upon slow-down in up direction

Upon receipt of the up signal, the operator of car B starts his car upward. Upon approach of car B to the fourth floor, the brush B70 (lower right part of Fig. 3) engages the stationary segment B74, thereby completing a circuit for the stopping relay BS of car B. The stopping relay BS accordingly closes to initiate a stopping sequence for car B, similar to that described above under the heading Automatic landing of car at calling floor. It will be recalled that the up call at the fourth floor was initially assigned to car A, and that the fourth floor up lantern 4UL of car A is illuminated. However, as soon as the high speed relay BV of car B drops out, a circuit for the fourth floor lantern B4UL of car B is completed as follows (lower right part of Fig. 2):

L1; B4UL; B54; B50, BW2; BV3; L2

As car B approaches the fourth floor, the selector brush B60 (right upper part of Fig. 3) engages the fourth floor segment B64, thereby completing a demagnetizing circuit for the up call relay 4UR which circuit will be obvious from the figure. Upon completion of this circuit, relay 4UR drops out, interrupting the circuit of the lantern 4UL of car A (Fig. 2) at contacts 4UR1. This completes the lantern transfer.

It will be noted that although an up hall call produces an instant signal for the particular car which has the up zone including the calling floor, the call is effective to stop the first car traveling in the up direction which attains a position suitable to answer the call, whether or not this car is the one to which the call was initially assigned.

We do not intend that the present invention shall be limited to the specific structural details, arrangement of parts or circuit connections herein set forth, as various modifications thereof may be effected without departing from the spirit and scope of our invention. We desire, therefore, that only such limitations shall be imposed as are indicated in the appended claims.

We claim as our invention:

1. In an elevator system having a group of cars operable in a hatchway from a terminal past a plurality of floors, call storing means for each car for recording desired stops of the corresponding car at any of said floors; motive apparatus individual to each of said cars; stopping means for each car responsive to the corresponding call storing means for controlling the corresponding motive apparatus to cause the car to stop at the

floors for which calls are recorded; and means effective a predetermined time interval after a selected one of said cars has left said terminal to prevent the assignment of calls to said selected one of said cars additional to the calls already assigned thereto.

2. In an elevator system having a group of cars operable past a plurality of floors, call storing means for each car for a predetermined direction 10 of car motion for recording desired stops of the corresponding car at any of said floors; initiating means for rendering said call storing means for each car operable when the corresponding car is in a predetermined condition suitable for answering calls in said predetermined direction; and time-controlled means for restricting the effectiveness of said call storing means for a selected one of said cars as a function of the elapsed time following operation of said initiating means 20 to render the corresponding call storing means effective.

3. In an elevator system having a group of cars operable past a plurality of floors, call storing means for each car for a predetermined direction 25 of car motion for recording desired stops of the corresponding car at any of said floors; initiating means for rendering said call storing means for each car operable when the corresponding car is in a predetermined condition suitable for answering calls in said predetermined direction; and time-controlled means effective a predetermined interval of time after operation of said initiating means in rendering said call storing means for a selected one of said cars operable, to thereafter 30 prevent the assignment of calls to said selected one of said cars additional to the calls already assigned thereto.

4. In an elevator system having a group of cars operable past a plurality of floors, down call storing means for each car for recording desired stops of the corresponding car on down trips at any of said floors; initiating means for rendering said down call storing means for each car operable when the corresponding car is in a predetermined condition suitable for the answering of down calls; and time-controlled means for restricting the effectiveness of said down call storing means for a selected one of said cars as a function of the elapsed time following operation 45 of said initiating means to render the corresponding down call storing means effective.

5. In an elevator system having a group of cars operable past a plurality of floors, call storing means for each car for recording desired stops of the corresponding car at any of said floors; 50 limiting means for controlling said call storing means to restrict the number of stops assigned to the individual cars; and time-controlled means, effective when the call storing means for a selected one of said cars has been in service for a predetermined interval of time, to restrict the number of stops assigned to said selected one of said cars.

6. In an elevator system having a group of cars operable past a plurality of floors, call storing means for each car for recording desired stops of the corresponding car at any of said floors; individual quota means for each of said cars, each of said quota means being effective to limit the number of stops assigned to the corresponding car, and time-controlled means, effective when the call-storing means for a selected one of said cars has been in service for a predetermined interval of time, to limit the number of stops as- 70 signed to said selected one of said cars, irrespec- 75

tive of the condition of the corresponding individual quota means.

7. In an elevator system having a group of cars operable past a plurality of floors, call storing means for each car for recording desired stops of the corresponding car at any of said floors; motive apparatus individual to each of said cars; stopping means for each car responsive to the corresponding call storing means for controlling the corresponding motive apparatus to cause the cars to stop at the floors for which calls are recorded; individual quota means for said cars, each of said quota means being effective to limit the number of stops assigned to the corresponding car; and time-controlled means, effective when the call-storing means for a selected one of said cars has been in service for a predetermined interval of time, to limit the number of stops assigned to said selected one of said cars.

8. In an elevator system having a group of cars operable in a hatchway past a plurality of floors, call storing means for each car for recording desired stops of the corresponding car at any of said floors; zoning means for dividing the hatchway into zones of floors and for assigning each zone to one of said cars; motive apparatus individual to each of said cars; stopping means for each car responsive to the corresponding call storing means for controlling the corresponding motive apparatus to cause the cars to stop at the floors for which calls are recorded; individual limiting means for said cars, each of said limiting means being effective upon operation, to prevent the assignment of calls to the corresponding car additional to the calls already assigned thereto; and time-controlled means effective after a selected one of said cars has had a zone for a predetermined interval of time to thereafter prevent the assignment of calls to said selected one of said cars additional to the calls already assigned thereto.

9. In an elevator system having a group of cars operable in a hatchway past a plurality of floors, call-storing means for each car for recording desired stops of the corresponding car at any of said floors; switch means for registering desired stops at any of said floors; zoning means for dividing the hatchway into zones of floors and for assigning each zone to one of said cars; means, effective upon operation of said switch means, for operating said call storing means to assign a call to the car having the zone which includes the floor corresponding to the desired stop; individual limiting means for said cars, each of said limiting means being effective, upon operation, to prevent the assignment of calls to the corresponding car additional to the calls already assigned thereto; and time-controlled means, effective after a selected one of said cars has had a zone for a predetermined interval of time, to thereafter prevent the assignment of calls to said selected one of said cars additional to the calls already assigned thereto.

10. In an elevator system having a group of cars operable in a hatchway past a plurality of floors, call storing means for each car for recording desired stops of the corresponding car at any of said floors; switch means for registering desired stops at any one of said floors; zoning means for dividing the hatchway into zones of floors and for assigning each zone to one of said cars; means, effective upon operation of said switch means, for operating said call-storing means to assign a call to the car having the zone which includes the floor corresponding to

the desired stop; and time-controlled means, effective after a selected one of said cars has had a zone for a predetermined interval of time, to thereafter prevent the assignment of calls to said selected one of said cars additional to the calls already assigned thereto.

11. In an elevator system having a group of cars operable in a hatchway past a plurality of floors, call storing means for each car for recording desired stops of the corresponding car at any of said floors; switch means for registering desired stops at any of said floors; zoning means for dividing the hatchway into zones of floors and for assigning each zone to one of said cars; means, effective upon operation of said switch means, for operating said call storing means to assign a call to the car having the zone which includes the floor corresponding to the desired stop; and time-controlled means, effective after a selected one of said cars has had a zone for a predetermined interval of time, to thereafter prevent the assignment of calls to said selected one of said cars additional to the calls already assigned thereto, and effective to transfer the zone assigned to said selected one of said cars to the one of said cars having the next following zone for corresponding direction of car travel.

12. In an elevator system having a group of cars operable in a hatchway past a plurality of floors, call storing means for each car for recording desired stops of the corresponding car at any of said floors, switch means for registering desired stops at any of said floors; zoning means for dividing the hatchway into zones of floors and for assigning each zone to one of said cars; means, effective upon operation of said switch means, for operating said call storing means to assign a call to the car having the zone which includes the floor corresponding to the desired stop; and time controlled means, effective after a selected one of said cars has had a zone for a predetermined interval of time, to transfer the zone assigned to said selected one of said cars to the one of said cars having the next following zone for the corresponding direction of car travel.

13. In an elevator system having a group of cars operable in a hatchway from a terminal past a plurality of floors, call storing means for each car for recording desired stops of the corresponding car at any of said floors; switch means for registering desired stops at any one of said floors; zoning means for dividing the hatchway into zones of floors and for assigning each zone to one of said cars; means, effective upon operation of said switch means, for operating said call storing means to assign a call to the car having the zone which includes the floor corresponding to the desired stop; dispatching means for automatically providing signals for the starting of said cars from said terminal; and means effective upon the provision of a predetermined signal to a selected car for transferring the zone of the nearest car in the hatchway in advance of said selected car to said selected car.

14. In an elevator system having a group of cars operable in a hatchway from a terminal past a plurality of floors, call storing means for each car for recording desired stops of the corresponding car at any of said floors; switch means for registering desired stops at any of said floors; zoning means for dividing the hatchway into zones of floors and for assigning each zone to one of said cars; means, effective upon operation of said switch means, for operating said call

storing means to assign a call to the car having the zone which includes the floor corresponding to the desired stop; dispatching means for automatically providing signals for the starting of said cars from said terminal; and means effective upon the provision of a predetermined signal to a selected car for transferring the zone of all cars in the hatchway moving away from said terminal to said selected car.

15. In an elevator system having a group of cars operable in a hatchway from a terminal past a plurality of floors, call storing means for each car for recording desired stops of the corresponding car at any of said floors; switch means for registering desired stops at any of said floors; zoning means for dividing the hatchway into zones of floors and for assigning each zone to one of said cars; means effective upon operation of said switch means for operating said call storing means to assign a call to the car having the zone which includes the floor corresponding to the desired stop; dispatching means for automatically providing signals for the starting of said cars from said terminal; and means effective upon the provision of a predetermined signal to a selected car for preventing the assignment of calls to the nearest car to said terminal, moving away from said terminal.

16. In an elevator system having a plurality of cars operable past a plurality of floors, a plurality of groups of signal elements; each of said groups comprising a plurality of individual signal elements for one of said cars, for a predetermined direction of car travel, corresponding to a plurality of said floors; switch means for registering desired stops at any of said floors for said predetermined direction of car travel; selecting means effective upon operation of said switch means in registering a desired stop for a particular one of said floors, for immediately selecting and operating an individual signal element corresponding to said particular one of said floors; and time-controlled means for limiting the time interval during which said selecting means may select any individual signal element of a predetermined one of said groups.

17. In an elevator system having a plurality of cars operable past a plurality of floors, a plurality of groups of signal elements, each of said groups comprising a plurality of individual signal elements for one of said cars, for a predetermined direction of car travel, corresponding to a plurality of said floors; switch means for registering desired stops at any of said floors, for said predetermined direction of car travel; selecting means, effective upon operation of said switch means in registering a desired stop for a particular one of said floors, for immediately selecting and operating an individual signal element corresponding to said particular one of said floors; initiating means for rendering said selecting means effective to select and operate the individual signal elements of a predetermined one of said groups; and time-controlled means, effective a predetermined interval of time after operation of said initiating means, to thereafter prevent the operation of the individual signal elements of said predetermined one of said groups.

18. In an elevator system having a plurality of cars operable from a terminal past a plurality of floors, a plurality of groups of signal elements; each of said groups comprising an individual signal element for one of said cars, for the direction of car travel away from said terminal,

for each of said floors; switch means for registering desired stops at any of said floors for said direction away from said terminal; selecting means effective upon operation of said switch means in registering a desired stop for a particular one of said floors, for immediately selecting and operating an individual signal element corresponding to said particular one of said floors; dispatching means for distributively selecting cars for dispatch from said terminal and for providing dispatch signals for the selected cars; and means controlled by said dispatching means for rendering said selecting means effective to operate the signal elements of a predetermined group in response to selection of the corresponding car by said dispatching means, and for rendering said selecting means ineffective to operate said signal elements of said predetermined group in response to operation of said dispatching means in selecting a different car.

19. In an elevator system having a plurality of cars operable past a plurality of floors, a plurality of groups of call storing elements, each of said groups comprising a plurality of individual call storing elements for one of said cars, for a predetermined direction of car travel, corresponding to a plurality of said floors; switch means for registering a desired stop at any of said floors for said predetermined direction of car travel; selecting means effective upon operation of said switch means in registering a desired stop for a particular one of said floors, for immediately selecting and operating an individual call storing element corresponding to said particular one of said floors; and time-controlled means for limiting the time interval during which said selecting means may select an individual call storing element of a predetermined one of said groups.

20. In an elevator system having a plurality of cars operable past a plurality of floors, a plurality of groups of call storing elements, each of said groups comprising a plurality of individual call storing elements, for one of said cars, for a predetermined direction of car travel, corresponding to a plurality of said floors; switch means for registering desired stops at any of said floors for said predetermined direction of car travel; selecting means effective upon operation of said switch means in registering a desired stop for a particular one of said floors, for immediately selecting and operating an individual call storing element corresponding to said particular one of said floors; initiating means for rendering said selecting means effective to select and operate the individual call storing elements of a predetermined one of said groups; and time-controlled means, effective a predetermined interval of time after operation of said initiating means, to thereafter prevent the operation of the individual call storing elements of said predetermined one of said groups.

21. In an elevator system having a plurality of cars operable in a hatchway from a terminal, past a plurality of floors, a plurality of groups of call storing elements, each of said groups comprising an individual call storing element for each of said cars, for the direction of car travel away from said terminal, for each of said floors; switch means for registering desired stops at any of said floors for said direction away from said terminal; selecting means effective upon operation of said switch means in registering a desired stop for a particular one of said floors, for immediately selecting and operating an indi-

vidual call storing element corresponding to said particular one of said floors; dispatching means for distributively selecting cars for dispatch from said terminal and for providing dispatch signals for the selected cars; and means controlled by said dispatching means for rendering said selecting means effective to operate the call storing elements of a predetermined group in response to selection of the corresponding car by said dispatching means, and for rendering said selecting means ineffective to operate said call storing elements of said predetermined group in response to operation of said dispatching means in selecting a different car.

22. In an elevator system having a plurality of cars operable from a terminal past a plurality of floors, call storing means comprising an individual call storing element for each of said cars, for the direction of car travel away from said terminal, for each of said floors; switch means for registering desired stops at any of said floors for said direction away from said terminal; zoning means for dividing the hatchway into zones of floors and for assigning each zone to one of said cars; means effective upon operation of said switch means, for operating said call storing means to assign a call to the car having the zone which includes the floor corresponding to the desired stop; dispatching means for distributively selecting cars for dispatch from said terminal and for providing dispatch signals for the selected cars; and means controlled by said dispatching means for transferring the zone of the nearest car to said terminal on a trip away from said terminal, to the particular car having the zone extending away from said terminal, upon selection of said particular car for a dispatch signal.

23. In an elevator system having a plurality of cars operable from a terminal past a plurality of floors, call storing means comprising an individual call storing element for each of said cars, for the direction of car travel away from said terminal, for each of said floors; switch means for registering desired stops at any of said floors for said direction away from said terminal; zoning means for dividing the hatchway into zones of floors and for assigning each zone to one of said cars; means, effective upon operation of said switch means, for operating said call storing means to assign a call to the car having the zone which includes the floor corresponding to the desired stop; dispatching means for distributively selecting cars for dispatch from said terminal and for providing dispatch signals for the selected cars; and means controlled by said dispatching means for transferring the zone of any car in said hatchway on a trip away from said terminal, to the particular car having the zone extending away from said terminal, upon selection of said particular car for a dispatch signal.

24. In an elevator system having a plurality of cars operable from a terminal past a plurality of floors, call storing means comprising an individual call storing element for each of said cars, for the direction of car travel away from said terminal, for each of said floors; switch means for registering desired stops at any of said floors for said direction away from said terminal; zoning means for dividing the hatchway into zones of floors and for assigning each zone to one of said cars; means effective upon operation of said switch means for operating said call storing means to assign a call to the car having the

zone which includes the floor corresponding to the desired stop; dispatching means for distributively selecting cars for dispatch from said terminal and for providing dispatch signals for the selected cars, an individual floor lantern for each of said call storing elements, said floor lanterns being controlled by corresponding call storing elements to provide instant signals of desired stops; and means controlled by said dispatching means for transferring the zone of any car in said hatchway on a trip away from said terminal, to the particular car having the zone extending away from said terminal, upon selection of said particular car for a dispatch signal.

15 25. In an elevator system having a plurality of cars operable from a terminal past a plurality of floors, call storing means comprising an individual call storing element for each of said cars, for the direction of car travel away from said terminal, for each of said floors; switch means for registering desired stops at any of said floors for said direction away from said terminal; motive apparatus individual to each of said cars, stopping means for each car responsive to the corresponding call storing means for controlling the corresponding motive apparatus to cause the cars to stop at the floors for which calls are recorded; zoning means for dividing the hatchway into zones of floors and for assigning each zone to one of said cars; means, effective upon operation of said switch means, for operating said call storing means to assign a call to the car having the zone which includes the floor corresponding to the desired stop; dispatching means for distributively selecting cars for dispatch from said terminal and for providing dispatch signals for the selected cars; an individual floor lantern for each of said call storing elements, said floor lanterns being controlled by corresponding call storing elements to provide instant signals of desired stops; and means controlled by said dispatching means for transferring the zone of any car in said hatchway on a trip away from said terminal, to the particular car having the zone extending away from said terminal, upon selection of said particular car for a dispatch signal.

26. In an elevator system having a plurality of cars operable between an upper terminal and a lower terminal past a plurality of floors, call storing means for each car for recording desired stops of the corresponding car at any of said floors; individual quota means for said cars, each of said quota means being effective to limit the number of desired stops which can be recorded on the call storing means of the corresponding car; dispatching means for distributively selecting cars for dispatch from said terminals and for providing start signals for the selected cars; and means responsive to operation of one of said quota means when cars selected for dispatch are present at both of said terminals for causing said dispatching means to give start signals to both of said cars selected for dispatch.

65 27. In an elevator system having a plurality of cars operable between an upper terminal and a lower terminal past a plurality of floors, call storing means for each car for recording desired stops of the corresponding car at any of said floors; individual limiting means for said cars, each of said limiting means being effective, upon operation, to prevent the assignment of calls to the corresponding car additional to the calls already assigned thereto; dispatching means for distributively selecting cars for dispatch from said terminals and for providing start signals for the

selected cars; and means responsive to operation of one of said limiting means when cars selected for dispatch are present at both of said terminals for causing said dispatching means to give start signals to both of said cars selected for dispatch.

28. In an elevator system having a plurality of cars operable between an upper terminal and a lower terminal past a plurality of floors, call storing means for each car for recording desired stops of the corresponding car at any of said floors; individual limiting means for said cars, each of said limiting means being effective, upon operation, to prevent the assignment of calls to the corresponding car additional to the calls already assigned thereto; individual quota means

10

for said cars, for totalizing the calls assigned to the corresponding car and for operating the corresponding limiting means in response to a predetermined total of calls; dispatching means for distributively selecting cars for dispatch from said terminals and for providing start signals for the selected cars, and means responsive to operation of one of said limiting means when cars selected for dispatch are present at both of said terminals for causing said dispatching means to give start signals to both of said cars selected for dispatch.
